[57] **CLAIM**

The ornamental design for a housing for printed circuit boards, as shown and described.

DESCRIPTION

FIG. 1 is a top, left side and front perspective view of a housing for printed circuit boards showing my new design, the right side being a mirror image of the left side;

FIG. 2 is a top plan view thereof on a reduced scale, the bottom view being a mirror image;

FIG. 3 is a rear elevational view thereof on a reduced scale;

FIG. 4 is a top left side and front perspective view of a second embodiment of my design;

FIG. 5 is a top plan view thereof on a reduced scale, the bottom being a mirror image;

FIG. 6 is a rear elevational view thereon on a reduced scale; and

FIG. 7 is a sectional view on a greatly enlarged scale of the first embodiment taken along line 7—7 in FIG. 2, the second embodiment being similar thereto however including a spacer between the top and bottom sections.
